Micah C. Gunn(57) **CLAIM**

The ornamental design for a vice grip with slide hammer, as shown and described.

DESCRIPTION

FIG. 1 is a right side elevation view of a vice grip with slide hammer showing my new design, a vice grip and a slide hammer separated for clarity;

FIG. 2 is a left side elevation view thereof;

FIG. 3 is a top plan view thereof;

FIG. 4 is a bottom plan view thereof;

FIG. 5 is a front elevation view thereof;

FIG. 6 is a rear elevation view thereof; and,

FIG. 7 is an isometric view thereof.
